LOW FREQUENCY TRIANGULAR WAVEFORM GENERATOR

Joseph F. Brumbaugh, Niagara Falls, and Allen H. Retzlaff, Lockport, N. Y., assignors to the United States of America as represented by the Secretary of the Air Force

Application May 11, 1954, Serial No. 429,140

1 Claim. (Cl. 250—36)

It is the object of this invention to provide a triangular waveform generator having a period of the order of 6 to 10 seconds and a waveform of good linearity. The invention will be fully described in connection with a preferred embodiment thereof shown in the accompanying drawings, in which

Fig. 1 is a schematic circuit diagram of the triangular waveform generator; and

Fig. 2 shows a set of waveforms occurring at various places in the circuit of Fig. 1.

Referring to Fig. 1, pentode tube V₁ and its associated circuit constitute the triangular wave generator, the cathode follower stage V₂ being only for the purpose of isolating the generator from its load circuit. The triangular voltage wave is generated across condenser C₁, or across C₂ or C₃ depending upon the position of switch S₁. The falling portion of this wave, designated m in Fig. 2, is generated by the charging of C₁ from voltage source E₁ through resistors R₇ and R₈ and the control grid cathode path of V₁; the rising portion, designated n in Fig. 2, is generated by the discharge of C₁ through the anode-cathode path of V₁ and resistor R₉. The manner in which the circuit oscillates between these two conditions is as follows:

Assume voltages E₁ and E₂ to be removed and condenser C₁ to be fully discharged. Upon application of the voltages E₁ and E₂ at time t₀, C₁ begins to charge through R₇, R₈ and the grid-cathode path of V₁ causing a slight rise B in control grid voltage relative to the cathode of sufficient magnitude to provide a current flow from grid to cathode equal to the charging current. Since the potential across C₁ can not change instantaneously the anode voltage at t₀ equals the grid voltage and experiences the same slight rise B. Because the anode potential is below its cut-off value, there is no anode conduction at this time. The screen grid current, however, has its maximum value and this current flowing through R₄ reduces the screen grid voltage to its minimum value. Since the suppressor grid voltage is directly related to the screen grid voltage through the action of potential divider R₃—R₁—R₂, this grid also has its minimum voltage at this time.

As C₁ charges its voltage increases and the anode potential rises. This rise is made linear with respect to time by operating on the linear portion of the charging characteristic. Eventually, at time t₁, the anode potential becomes high enough that some of the electrons formerly going to the screen grid now pass through the suppressor grid and reach the anode. The resulting decrease in screen current causes a further increase in screen and suppressor voltages which in turn causes a still further increase in anode current and decrease in screen current. A regenerative condition therefore exists which produces an almost instantaneous transition at t₁ from a condition of zero anode current to a condition in which C₁ is discharging through the anode-cathode path of V₁ and resistors R₆ and R₉.

2

When anode conduction begins there is an immediate drop in anode potential due to this conduction and an equal drop in grid potential due to the fact that an immediate change in the voltage across C₁ is not possible. 5 This equal drop of anode and grid voltages is designated "A" in Fig. 2. At the instant when the control grid potential falls below the cathode potential R₉ and R₆ are introduced into the charging circuit of C₁ since the shunting effect of the grid-cathode path of tube V₁ is removed. 10 The effective charging voltage across C₁ therefore becomes less than the condenser voltage and as a result C₁ begins to discharge through V₁, R₆ and R₉.

During discharge the grid potential is determined by the discharge current flowing through relatively large resistor R₉. This results in a negative feedback action which holds the discharge current flowing through V₁ constant thus insuring a linear portion n of the triangular wave.

As C₁ discharges the anode potential falls until eventually the potential is reduced to the point at which some of the electrons fail to penetrate the suppressor grid and return to the screen grid. This increases the screen current which lowers its potential and also that of the suppressor grid due to the coupling between these grids. 20 This results in a still further decrease in anode current and increase in screen current so that a regenerative situation exists that rapidly cuts off anode conduction in V₁. This event, at t₂, marks the end of the cycle. Condenser C₁ now begins to recharge through R₇, R₈ and the control grid-cathode path of V₁ starting a new cycle of operation.

Resistor R₇ is made variable in order to provide a control over the charging rate of the capacitor and to permit it to be made equal to the discharge rate through the tube. Resistor R₂ is a stability control which establishes the limit of bias on the suppressor grid and can also be adjusted to compensate for differences in individual tubes. With the parameters shown in Fig. 1, the period of the triangular wave with condenser C₁ is about 6 seconds, 25 with C₂ about 8 seconds and with C₃ about 10 seconds.

We claim:

A low frequency triangular wave generator comprising: a vacuum tube having a cathode, a control grid, a screen grid, a suppressor grid and an anode; a condenser having one terminal directly connected to said anode and the other terminal directly connected to said control grid; a source of direct current having positive and negative terminals; means directly connecting said cathode to a point on said source between said positive and negative terminals; a resistance connected between said anode and the positive terminal of said source; a first potential divider connected between said positive terminal and said cathode; a resistance connected between said control grid and an intermediate point on said first potential divider; 30 a second potential divider connected between said positive and negative terminals; a direct connection between said screen grid and a point on said second potential divider having lower potential than said positive terminal; a direct connection between said suppressor grid and a point on said second potential divider located between the point of connection of said screen grid and said negative terminal; and an output circuit connected to said control grid and said anode.
